SAMUEL B. GOLD, OF INDEPENDENCE, MISSOURI, ASSIGNOR TO WEBER ENGINE COMPANY, OF KANSAS CITY, MISSOURI, A CORPORATION OF IOWA.

STARTING ATTACHMENT FOR TWO-CYCLE INTERNAL-COMBUSTION ENGINES.

Application filed December 22, 1919. Serial No. 346,541.

To all whom it may concern:

Be it known that I, SAMUEL B. GOLD, a citizen of the United States, residing at Independence, in the county of Jackson and State of Missouri, have invented certain new and useful Improvements in Starting Attachments for Two-Cycle Internal-Combustion Engines, of which the following is a specification.

- 10 This invention relates to starting attachments for two cycle internal combustion engines. As well known two cycle engines, particularly those of the valveless type, are very desirable because they can be operated 15 with less attention and repair than engines equipped with valves. The chief objection to their use has been the difficulty of starting them, and attempts have been made to produce engines of this type having equipment 20 to facilitate the starting by pumping a sufficient volume of combustible mixture into the cylinder and compressing such mixture. To accomplish this the attendant has been compelled to rock or oscillate the 25 fly-wheel, the movement of the wheel in one direction sucking the combustible mixture into the pump chamber end of the cylinder, and the reverse movement compressing the charge and by-passing it to the opposite end 30 of the cylinder. In practice, it has always been necessary to repeat these rocking or oscillating operations a number of times, because it was believed the piston must not be withdrawn a sufficient distance to uncover 35 the exhaust port, and several of such limited piston movements were necessary to accumulate a sufficient volume of the mixture to effect the starting of the engine. In the operations of the fly-wheel the labor of the 40 attendant grew more fatiguing because of the increased resistance offered by the compression of the mixture which increased in volume with each suction movement of the piston.
- 45 I have found that it is possible to supply the cylinder of an engine of the type mentioned, with a starting charge by first turning the fly-wheel enough to withdraw the piston for its full stroke, then cutting off 50 the supply of mixture to the cylinder and then rocking the fly-wheel backward to compress the charge in the cylinder and trip the magneto to explode such charge, after which, operation occurs with the regular ports of

the engine, and this without regard to 55 whether the engine is of the valveless two or three port type.

My object, therefore, is to produce an internal combustion engine of the valveless two cycle type, provided with auxiliary air 60 and gas ports at the head end of the cylinder so that the engine can be started by one forward and one reverse turning movement, and in which this operation can be accomplished by a single attendant. 65

A further object is to provide starting equipment of simple, durable and inexpensive construction, which can be applied cheaply to engines already in use or which forms part of the equipment of an engine 70 when built.

To these ends the invention consists in certain novel and useful features of construction and combinations of parts, as herein-after described and claimed; and in order 75 that it may be fully understood, reference is to be had to the accompanying drawing, in which:

Figure 1, is a view chiefly in side elevation, of an internal combustion engine of the 80 valveless two-cycle type, equipped with starting mechanism embodying the invention.

Figure 2, is an enlarged section on the dotted line II, of Figure 1. 85

Figure 3, is a vertical section on line III—III of Figure 2.

In the said drawing, 1 indicates the crank case, 2 the crank shaft, 3 one of the fly-wheels, 4 the cylinder, and 5 the head of the 90 cylinder of a conventional type of two cycle engine.

A pipe 6 leads from a suitable gas supply, not shown, to the customary or regular gas port 7, indicated by dotted lines in Figure 1, and said cylinder is likewise provided with the customary air supply port A and exhaust port B, not detailed. 95

The head of the cylinder is provided with a port 8, disposed beyond the extreme rearward position which the piston 9 attains in the operation of the engine. A valve casing 10 is rigidly secured to the cylinder head 5, and around port 8, and connecting with said casing at opposite sides thereof is an air inlet pipe 11 and a gas supply pipe 12, the latter constituting, if desired, an extension 100 of the gas supply pipe 6.

Mounted in said casing 10, is a valve 13, provided with a port 14 and a port 15, which ports are adapted to simultaneously register with pipes 11 and 12, respectively 5 when the valve is open, and said ports also connect with a third or axial port 16, communicating with the port 8.

The outer end of the valve casing is closed by a cap 17, through which a reduced portion of the valve extends, and mounted rigidly on said reduced portion is a handle 18 whereby the valve may be turned. In preferred construction, said handle is pivotally connected by a rod 19 with a hand lever 20 10 mounted upon a sector 21 secured to the frame of the engine at the crank shaft end thereof, so that said lever shall be conveniently accessible to the attendant when starting the engine.

20 Assuming that it is desired to start the engine and that the piston thereof is at the rearward end of its stroke, the operator steps upon one of the spokes of the fly-wheel—these engines usually have two fly-wheels 25 at opposite sides—and grasps the rim of the wheel at a higher point so that he can add his weight to the pulling force which he applies in the rocking of the wheel to effect piston movement from the position *a* to the 30 position *b*, it being understood that preliminary to this rocking movement he has first manipulated lever 20 to establish connection between the air and gas pipes 11 and 12 respectively, and the port 8, so that in said 35 piston movement a suctional action is produced which draws into the cylinder a mixture of air and gas. As this rocking movement ends the operator grasps and operates lever 20 so as to turn valve 13 sufficiently to 40 dispose its passages 14 and 15 out of registration with the air and gas pipes mentioned, this action sealing or closing port 8. The operator now steps to the opposite side 45 of the wheel and as before, disposes his weight upon one of the elevated spokes, and grasping the rim, rocks said wheel in the reverse direction to that first mentioned, this action moving the piston rearward or toward its original position, and compressing 50 the charge of a combustible mixture of air and gas between the piston and the head of the cylinder. At the proper time in this movement, the customary magneto, not shown, is tripped to produce a spark in the 55 cylinder and thereby fire or explode the compressed mixture therein. The explosion of the charge drives the piston forward, and the engine continues to operate thence for-

ward under its own power and with the regular ports.

From the above description it will be apparent that I have produced starting mechanism for two cycle internal combustion engines, embodying the features of advantage set forth as desirable in the statement of the object of the invention, and which is obviously susceptible of modification in minor particulars without departing from the principle of construction and mode of operation involved.

70 I claim:

1. A valveless two-cycle gas engine having a port in the head end of the cylinder, a valve casing, a valve therein having a passage communicating with the said port and also having air and gas passages communicating with the first-named passage, an auxiliary gas and air supply in communication with the said air and gas passages of the valve for supplying combustible mixture to the cylinder under suction produced by the advance of the piston, and manual means to actuate the valve to close the supply of combustible mixture to the engine at the end of such advance movement of the piston, to trap such mixture and thereby effect its compression through the ensuing reverse movement of the piston.

2. A valveless two-cycle gas engine provided with a cylinder port at its head end beyond the rearmost travel of the piston of the engine, a valve casing, a three-way valve journaled in the casing with one of its ports in connection with said cylinder port, an air supply in connection with one of the other ports of said valve, a gas supply in connection with the third port of said valve, and manually operable means for closing said valve to cut off the supply of air and gas to the cylinder.

3. A valveless two-cycle gas engine provided with a cylinder port at its head end beyond the rearmost travel of the piston of the engine, a valve casing, a three-way valve journaled in the casing with one of its ports in connection with said cylinder port, an air supply in connection with one of the other ports of said valve, a gas supply in connection with the third port of said valve, a hand lever, and means for transmitting power from the hand lever to said valve to close the latter.

In testimony whereof, I affix my signature.

SAMUEL B. GOLD.
